UNITED STATES PATENT OFFICE.

PERCY A. E. ARMSTRONG, OF LOUDONVILLE, NEW YORK.

PROCESS OF AND APPARATUS FOR REMOVING SAND FROM HOLLOW DRILL-RODS AND THE LIKE.

1,311,866.

Specification of Letters Patent.

Patented Aug. 5, 1919.

Application filed January 17, 1919. Serial No. 271,613.

To all whom it may concern:

Be it known that I, PERCY A. E. ARMSTRONG, a subject of the King of Great Britain, and a resident of Loudonville, county of Albany, and State of New York, have invented certain new and useful Improvements in Processes of and Apparatus for Removing Sand from Hollow Drill-Rods and the like, of which the following is

10 a specification.

The present invention relates to a process of removing sand from tubular bodies, such as hollow drill rods and the like, and apparatus for carrying out the process.

15 The term "sand" is used herein as a convenient designation for finely divided material used in cores for bored billets from which elongated tubular bodies, as hollow drill rods and the like, are made by working the billet and core for elongation and reduction of cross section, as by heating and rolling, after which the core is removed. Material such as dead burned magnesite or talc powder, lime, zirconia and the like is preferred for this purpose, but various other materials may be used, all of which may be conveniently referred to as sand.

20 Where the core contains a metallic member in the form of a rod or the like, the removal of the sand is facilitated by withdrawing the rod first, leaving an opening in the sand. The rod may have projections on its surface, or the end which goes through the sand and comes out last may be battered or deformed, which breaks up the sand layer to a greater or less extent, making its removal easier. The present invention is also applicable to removal of cores of other forms, as the all sand core, which, however, 25 is likely to be more caked and hard to remove than the rod centered core.

25 It has heretofore been proposed to remove sand cores by means of air admitted through a pipe or drill inserted in the bore of the 30 drill rod or other tubular body. In such case the sand is carried out through the narrow annular passage adjacent to the bore walls, and when the latter are rough or uneven this interference with the free passage of the particles, making the removal comparatively slow and in some cases even causing such passage to get choked up and closed.

In accordance with my invention the sand is withdrawn through a pipe inserted in the bore, by which means an increase in the width of passage is available, and as the sand is removed through the smooth walled interior of such pipe there is none of the interference with its passage which may result from its withdrawal in contact with the comparatively rough walls of the bore in the drill rod or other tubular body produced from the cored billet.

35 Air or other fluid is introduced through the annular passage outside the pipe, and this air is preferably under high pressure. There is, of course, none of the obstruction to the inward movement of air through this annular passage which is encountered when it is attempted to remove the sand by such passage.

40 In the drawings, Figure 1 is a diagrammatic longitudinal sectional view of an apparatus by which the invention may be carried out. Fig. 2 is a sectional detail view, on an enlarged scale, of a hollow head for introducing air under pressure, and Fig. 3 is a side view, partly in section, of the entering end of a pipe for sand removal. The drawings show but a single unit, which may, of course, be duplicated or supplied in any desired multiples as needed.

45 The drill rod or other tubular body 10 is supported in any desired way, as on standards 11, and may be clamped thereon as by screws 11'. The standards may be open at one side to permit ready insertion and removal of the drill rod. One or both of the heads 12 is movable, as by being bolted in place by bolts 13 passing through slots 14. This permits the tubes 10 to be readily put into place when they are to be cleaned out, and also permits ready removal thereof after the cleaning is done. Flexible piping, hinge joints in the pipe connections or the like may be used to permit such movement of the head or heads 12.

50 The heads 12 are clamped in place as by means of levers 15 having cams 16 and are made air tight by suitable gaskets 17 of rubber or the like. If desired, locking cam levers 15^a may be placed on a member 15^b of ring shape pivoted to the head 12 at 15^c and locked or latched in place as by means 55 of a lever 15^d (see Fig. 2), and various

other forms of securing means may be used. The use of gaskets may be avoided, if desired, by providing the head 12 with an elongated socket adapted to have a fairly close fit over the end portion of the drill rod.

The pipes 18 which are introduced into the tube 10 may have a cutting end which, for example, may be substantially chisel-shaped, as shown at 19, Fig. 3. The sand 10 is withdrawn through the pipes 18 as by vacuum from an air pump 20, suitable means, such as a separator 21, being preferably utilized to separate out the sand before the air reaches the pump. A pump 15 capable of producing substantially high vacuum is preferably used. Air under compression may be supplied to the heads 12, as from a compressor 22, and enters the end of pipe 18 after passing through the annular passages 23 between the pipes 18 and the walls of the bore 10' of the tubular body 10, which passages 23 are in communication with the interior of the hollow heads 12. The directions of air movement 20 are indicated by arrows.

Means are preferably supplied to advance the pipes 18 and keep them up to the unremoved sand. For illustration I have shown a follower 24 urged by a weight 25 against the projecting end 26 of the pipe 18 for the purpose of advancing the pipe as the sand is removed. Various means may, however, be resorted to for advancing or operating the pipe, if desired, as, for example, it may 30 be manipulated by a workman or may be actuated by suitable automatic tools for making use of its cutting edges to loosen and free the particles of sand, as will be readily understood. The pipe itself may be somewhat 35 heavier and stronger than heretofore, since the annular passage around it is utilized for entrance of incoming air only and is not used for discharging sand.

When removing sand for apertured sand 45 cores, as shown at 27, Fig. 2, if the sand is being removed from but one end at a time the other end may be plugged, as shown at 28, Fig. 2. When working from both ends, as in Fig. 1, the all sand core or the apertured core may be used, as the air in the intermediate core portion, if open, is under substantially balanced pressures.

It will be seen that the air entering under pressure about the walls of the bore is 55 adapted to keep the bore clean, and its impact upon the sand is close to the walls of the bore, tending to keep the sand core cut away close to the bore walls, which is advantageous in securing its rapid and complete removal, particularly if there is already an 60 opening at the center of the core. The action of the entering air is indicated roughly in Fig. 2. The portions of the sand core adjacent to the bore walls, and indicated at 29, 65 29, receive the impact of the entering air and

tend to be cut away first, whereupon the portions 30, 30, adjacent to the central bore 27, being deprived of support from the bore walls and already more or less broken up by the withdrawal of the rod therefrom, are 70 readily disintegrated and removed. The tubular member 10 may, of course, be subjected to vibration, jarring and the like action to assist in the freeing and removal of the sand.

The outgoing sand and air pass freely through the opening in the smooth walled pipe 18. That a wider passage may be obtained in this way than in the case of removal through the passage between the pipe 80 and the bore walls may be seen from the following example, which, of course, is for illustration only and applies more particularly to hollow steel drill rods of certain sizes, and does not limit me to any particular dimensions.

If the bore of the tube is, say, $\frac{3}{8}$ " and the pipe $\frac{1}{4}$ " with $\frac{3}{16}$ " walls and $\frac{1}{16}$ " bore, the average width of the annular opening about the pipe is $\frac{1}{16}$ ", or, at most, when the pipe 90 lies at one side of the bore it may be $\frac{1}{8}$ ", which is the largest size of particle that can be removed through this annular passage, whereas with removal through the pipe a clear $\frac{1}{16}$ " passage is secured and the walls 95 with which the outgoing particles come into contact are smooth and not rough, as the bore of the tube may be. In this case it will be noted that the total cross section of the annular passage about the pipe is considerably more than that of the hole in the pipe, but the width or diameter of the latter, which determines the size of particles that can be removed, is 50% more than the greatest width of the former and three times the 105 average width thereof. This is of advantage with any type of core, but is of particular advantage with the apertured cores produced by placing a rod in the sand core, which, when elongated, as by rolling, with 110 the billet and the envelop of sand, is withdrawn, leaving a central aperture in the sand and leaving the sand itself in more or less broken up condition.

It should be noted that when air is introduced under pressure it is not essential in all cases that vacuum be applied to the passage within the pipe, and, reversely, when vacuum in the pipe is employed it is not essential in all cases that the air entering 11 around the pipe be under pressure, but preferably both are employed. Other fluid media may, of course, be used instead of air, which, however, is the convenient and preferable medium to be used.

I claim:

1. The process of removing core sand from bores of tubular bodies which consists in forcing compressed air into the bore while confining same so as to discharge primarily 1

against the sand adjacent to the bore walls and loosen it therefrom, and in removing the loosened sand.

2. The process of removing core sand from bores of tubular bodies which consists in producing a central aperture in the sand core, in forcing compressed air into the bore while confining same so as to discharge against the sand substantially closely adjacent to the bore walls, and removing the loosened sand when freed from the bore walls.

3. The process of removing sand cores from tubular bodies which consists in inserting a pipe therein and removing the sand through the pipe by suction, the sand passing out through the pipe with the air which enters the bore through the annular passage between the pipe and bore walls.

20 4. The process of removing core sand from tubular bodies which comprises introducing a pipe in the bore thereof, forcing in compressed air through the annular passage between the pipe and the bore walls, and discharging the air and sand carried therewith through the pipe.

5. The process of removing core sand from tubular bodies such as drill rod and the like, which comprises inserting in the bore thereof a pipe having a bore of width greater than the maximum width of the annular space between the pipe and the bore walls of the tubular body, forcing in compressed air through the annular passage between the pipe and the bore walls, and applying vacuum within the pipe, whereby the sand is dislodged and withdrawn through the pipe.

6. The process of making tubular bodies such as drill rod and the like which comprises putting a metallic rod in the sand core of a bored billet, working the billet and core for elongation and reduction of cross section as by rolling, withdrawing the rod whereby the sand of the core is left

with an opening therein and in more or less broken up condition, introducing a pipe into the bore of the tubular body, entering air therein through the narrow passage about the pipe whereby the sand adjacent to the bore walls is dislodged by incoming air, and withdrawing the air and sand through the interior of the pipe.

7. The process of removing core sand from tubular bodies having a sand core with a metal rod therein which comprises deforming the following end of the rod and withdrawing same through the core sand, introducing a suction pipe within the bore of the tubular body whereby the sand is removed through the pipe and air is admitted through the annular passage about the pipe adjacent to the bore walls to dislodge the sand from the walls of the bore.

8. Apparatus for removing core sand from tubular bodies which comprise a suction pipe adapted to be inserted in the bore of the tubular body, vacuum means for drawing air and sand therethrough, and air compressing means adapted to discharge air under pressure into such bore by the annular passage between the pipe and the bore walls.

9. Apparatus for removing core sand from tubular bodies which comprise hollow heads adapted to be clamped to the opposite ends of the tubular body, one at least of such heads being movable to permit putting the tubular body in place, suction pipes adapted to be passed through such heads and into the bore in the tubular body, means for drawing air and sand through said pipes, and air compressing means adapted to supply said under pressure to the interior of the hollow heads and to discharge same into the bore in the tubular body by the annular passages between the pipe and the bore walls.

In testimony that I claim the foregoing, I have hereto set my hand, this 14th day of January, 1919.

PERCY A. E. ARMSTRONG.
